UNITED STATES PATENT OFFICE.

JACK E. PYRTLE, OF SAN FRANCISCO, CALIFORNIA, ASSIGNOR TO SERVICE PRODUCTS MANUFACTURING CO., OF CHICAGO, ILLINOIS, A CORPORATION OF ILLINOIS.

FOUNTAIN BRUSH.

Application filed February 23, 1924. Serial No. 694,675.

To all whom it may concern:

Be it known that I, JACK E. PYRTLE, a citizen of the United States, and a resident of San Francisco, county of San Francisco, State of California, have invented a new and useful Fountain Brush, of which the following is a specification.

This invention relates to fountain brushes wherein the handle forms a receptacle for whatever fluid it is desired to use in the brush, and particularly to the type of such brushes which are adapted to hold volatile cleaning liquid such as benzol and the like for the cleaning of typewriter type, removing spots from clothing and other cleaning purposes.

The objects of my invention are to effect improvements in a brush of this kind resulting in utmost simplicity and consequent cheapness of production, while at the same time providing a serviceable article having a reliable control for the liquid feed to the hairs of the brush, a perfect closure, an easily removed tip so that the liquid may be ejected freely to any spot without the medium of the hairs if desired, an easily refilled reservoir, and a sight indicating reservoir for the fluid.

I attain the objectives outlined by the fountain brush structure shown in the accompanying drawings and in which:

Figure 1 is a perspective view of my complete brush as fitted with a transparent or glass handle reservoir.

Figure 2 is an enlarged central section of the upper portion of the brush showing its interior construction.

Figure 3 is a cross section of Figure 2 along the line 3—3 thereof showing the liquid feed.

Figures 4 and 5 show optional methods of securing the removable end to the reservoir handle.

In further detail the drawings show at (1) a hollow handle or reservoir for the liquid, in this illustration a glass tube forms the handle so that the liquid (2) is visible thus indicating at a glance whether the reservoir is full or empty.

The lower end (3) of the tubular handle is closed and at the upper end is fitted a cork or other stopper (4) having a metal gripping flange (5) and having an extension carrying a ferrule (6) forming a holder for the brush hairs (7).

In Figure 2 the interior arrangement is shown and the ferrule (6) is seen to be closed at the lower end (8) with a threaded tube (9) extending into the ferrule and which tube is closed at its inner end by a small plug (10).

The brush hairs (7) are held in the ferrule by the latter, being crimped or contracted at the outer edge as shown at (11). The ferrule is supported by engagement of its threaded tube (9) with an exteriorly threaded stem extension (12), or feed pipe, passing through the stopper (4), and the feed pipe is held securely to the stopper by a washer (13) riveted to one end, and clamped by the flange (5) which is threaded over the pipe.

Within the pipe is a liquid passage (14) terminating at the upper end in a very small orifice (15). The extreme upper end of the feed pipe is rounded as shown at (16) so that upon screwing the ferrule down over the pipe, the end impinges the block (10) and thereby closes off the small orifice (15).

Small liquid feeding passages extend from between the tube space and the hairs of the brush either taking the form of perforations (17) in the tube or the form of slightly flattened sides of the plug (10) as shown at (18), see Figure 3, so that when the ferrule is unscrewed slightly to uncover the orifice the liquid will run through the passages and into the hairs of the brush. To get a quick action the brush may be given a violent shake or two to start the flow.

It is desirable that the ferrule screw snugly over the threads of the extension stem (12) so that the liquid will not back up along the threads during use.

No air vent is ordinarily necessary in the reservoir as the cleansing liquids used are usually of such a volatile nature that their vapors readily take up the space of the ejected liquid, and an atmospheric balance is also established during moments of non-use of the brush when the ferrule is slightly unscrewed as the passage (14) is in communication with atmospheric pressure through the hairs of the brush.

Instead of the stopper fitting within the hollow handle as described, it may take the form of a sleeve (19) surrounding the handle and having a gasket ring (20) interposed as shown in Figure 4, or it may be screwed to the outside of the handle as

shown in Figure 5 in which latter case it would be desirable that the handle be made of a metal tube.

Having thus described my invention it will be seen to effect the desired objects in an extremely simple and cheap way and it is the construction shown including reasonable modifications as may come within the spirit of the invention that I wish to cover in my claims.

I claim:

1. A fountain brush comprising a reservoir handle with a stopper at one end with a threaded pipe extending therethrough and projecting therefrom, a bristle carrying tubular element surrounding and securing the bristles and having a threaded socket screw-

ing over the pipe, said socket having a stop adapted to abut and close the end of the pipe upon screwing the element, and a port 20 from the socket to the bristles adjacent the stop.

2. A fountain brush comprising a tubular reservoir handle with a stopper frictionally fitting one end, a pipe threadedly engaging and extending through the stopper and clamped thereagainst by nuts on the pipe at opposite sides of the stopper, a brush head having a retaining ferrule and screwed on the pipe, and a valved port between the pipe and brush head closed or opened by screwing the ferrule.

JACK E. PYRTLE.
